UNITED STATES PATENT OFFICE.

FOREST V. DETWILER, OF CHICAGO, ILLINOIS.

COOKING APPARATUS.

1,270,386.

Specification of Letters Patent. Patented June 25, 1918.

Application filed March 30, 1914. Serial No. 828,135.

To all whom it may concern:

Be it known that I, FOREST V. DETWILER, a citizen of the United States, residing at Chicago, in the county of Cook and State of Illinois, have invented certain new and useful Improvements in Cooking Apparatus, of which the following is a specification.

This invention relates to improvements in cooking apparatus designed for the use of fluid fuel and one of the objects of the invention is to provide an improved portable device of this character, having means whereby the different cooking operations may be simultaneously performed in different parts of the apparatus, by the heat from a single burner, and means whereby the burner may be shifted to be used for broiling.

A further object is to provide an improved device of this character having a plurality of stove holes and means whereby the heated air from the burner will be equally distributed to the stove holes.

To the attainment of these ends, and the accomplishment of other new and useful objects as will appear, the invention consists in the features of novelty in substantially the construction, combination and arrangement of the several parts hereinafter more fully described and claimed and shown in the accompanying drawings illustrating the invention, and in which:

Figure 1 is a perspective view of an improved apparatus of this character constructed in accordance with the principles of this invention.

Fig. 2 is a bottom plan view partly broken away of the top of the base of the apparatus.

Fig. 3 is a front elevation of the apparatus.

Fig. 4 is a vertical longitudinal sectional view on line 4-4, Fig. 3.

Fig. 5 is an irregular sectional view taken on line 5-5, Fig. 4.

Fig. 6 is a detail sectional view of the gas valve connection.

Fig. 7 is a horizontal sectional view taken on line 7-7, Fig. 5.

Referring more particularly to the drawings and in the preferred form of the invention, the base of the apparatus is hollow and comprises a bottom 10, sides 11 and front and back walls 12, 13 and the back wall preferably extends for some distance above the remaining walls for a purpose to be set forth. These walls, with the exception of

the extending portion of the rear wall, are preferably insulated to prevent loss of heat and to conserve the heat within the base. The base of the apparatus may be of any desired size and configuration and is preferably supported by legs 14, the base being assembled in any suitable manner preferably by bending portions of the lower extremities of the upright walls back upon themselves to form seats which receive the flanges 16 on the bottom 10, and the parts are secured in any suitable manner.

Within the base thus formed, is arranged two upright partitions 17 which extend lengthwise of the base, the forward edge thereof abutting the inner face of the front wall 12 on opposite sides of the door opening 18 which latter is closed by a suitable closure or door 19, the door opening being arranged preferably to extend to the base 10.

Another partition 20 is arranged in the base preferably adjacent the rear wall 13 thereof so as to limit the depth of the chamber formed by the partitions 17, and a cover 21 extends over the space formed by the partition 20 and the adjacent wall 13 as well as the partitions 17 to prevent the heated air from entering such space and in which space the heat units would be lost.

These partitions 17 extend from the bottom 10 of the base and preferably terminate short of the top 22, which latter rests upon the walls of the base and is secured in position in any suitable manner. The top 22 is provided with stove holes 23 therethrough and depending from the lower face of the top are flanges 24, 25 which coöperate with the partitions 17 to form the burner space or chamber. The partitions 25 are preferably rounded or curved as shown to prevent the heated air and gases from entering the corners at the front of the base, while the partitions 24 are arranged so that they will converge from the sides of the base, at points adjacent the forward extremity thereof toward the rear of the base for directing the products of combustion and heated air in the base to the outlets 26, 27. A damper or valve 28 may be provided for controlling the outlet 27.

The partitions 17 are preferably formed of sheet material and are bent so as to form flanges arranged at the top and the bottom thereof, the lower flanges rest upon the base 10, while the uppermost flanges serve as supports for horizontal partition members 29,

and upon these flanges also rest the lower extremities of the flanges 24, 25. The partitions 17 are also preferably shaped to form a support 30 upon which another horizontal 5 partition 31 rests, and a spacing member 32 is arranged between the partition members 29, 31 for holding them spaced, and this spacing member may be secured to the respective sides 11, of the base for holding the 10 partitions 29, 31 in position. Insulating material 33 is provided for the spaces between the partitions 29, 31 and the top 22. The partitions 17 may also be provided with inwardly projecting portions 34, to form a 15 guide way beneath which a removable tray 35 stands and which tray is adapted to be inserted into the base through the door opening 18, to rest upon the bottom 10 thereof, the insertion of the tray 35 being limited 20 by the partition 20.

A burner 36 of any desired configuration is arranged within the burner space or chamber thus formed and this burner is mounted in such a manner that it will be 25 spaced above the tray 35 sufficiently to permit it to be rotated, so that the heated air or products of combustion therefrom may be directed to the stove holes 23 or to the tray 35.

30 In order to equally distribute the products of combustion to all of the stove holes, there is provided a deflector 37 which is preferably detachably connected to the top 22 of the base to depend therefrom and is 35 of a configuration to extend over a considerable area of the under face of the top of the base between the stove holes. The body of the deflector 37 tapers from the top 22 to a point above and in close proximity to the 40 burner 36, so that when the burner is lighted, the flame will strike the deflector, which also acts as a spreader, and will direct the flame and products of combustion to the stove holes. The spreader plate also serves 45 to strengthen the top plate of the base and holds it against warping. In order to support combustion, air openings 39 may be provided in the side walls 11 and similar air openings 40 are provided in the partition 17, 50 so that air entering the openings 39 will pass into the chamber 41 formed by the partitions 17 and side walls and a horizontal partition 31 and the base 10, and from these chambers will pass through the openings 40 55 into the burner space.

Arranged a suitable distance above the base of the apparatus and supported by the extension of the rear wall 13, and uprights 42 arranged at the sides of the base, and at 60 the rear thereof, is an oven designated generally by the reference numeral 43, which extends only a short distance over the base from the rear thereof. A partition 44 is arranged between the uprights 42 and is 65 spaced from and arranged parallel with the

back 13, and this partition 44 extends from the upper face of the top 22 of the base to the bottom 45 of the oven. Uprights 46 are arranged between the partition 44 and the extension of the back 13 above the base, to 70 form a flue, and which flue has communication with the outlet opening 26 in the top of the base. The bottom of the oven is provided with an inlet opening 47 from which a tapering flue 48 depends, and which tapering flue is provided with a flange portion 49 adapted to be inserted into the flue 47, so that when the damper 50 in the flue 57 is opened, the heated gases will pass from the base into the flue 47 to be discharged into 80 the oven 43 below the bottom 51 of the compartment in the oven, and is directed beneath the bottom of the compartment by means of a curved deflector 52. The sides 53 of the oven compartment are spaced from 85 the side walls 54 of the oven proper, to form circulation passages 55 which communicate with the passage beneath the oven compartment, and a similar passage 56 is arranged at the rear of the oven compartment and 90 communicates with the passages 55. Thus it will be seen that when the heated air is discharged from the flue 47 into the oven it will be prevented from passing into the passage 56 by the deflector 52, and will be 95 caused to flow about the compartment in the oven and into the passage 56 from where it will pass out of the outlet opening 57 when the damper 58 is opened. A portion of the heated air will also pass into the oven compartment through the openings 59 in the walls 53 thereof. Obviously supports 60 may be provided in the oven compartment.

In order to permit the burner to be rotated, any suitable connection may be provided between the burner and the gas supply tube 61. For this purpose, a portion of the burner projects through a suitable bearing 62 in one of the side walls of the base and is provided with a cup or chamber 110 portion 63 having a closed extremity 64 provided with an opening therethrough having a flange 65 therearound. A tube 66 having a valve 67 therein, and which tube telescopes with the tube 61, projects into the cup 63 through the opening 64, and in order to support the tube 66, a suitable support 68 may be provided and through which the tube passes. Thus it will be seen that the gas will be discharged into the cup 63 and 115 will flow from there to the burner. The burner is adapted to be reversed by means of a handle 69 connected with the cup 63, and the bracket 68 is so shaped that it will coöperate with the handle 69 to limit the 120 degree of rotation of the burner and to assure its proper positioning.

Obviously the oven is provided with a suitable door opening having the usual door or closure 70 therefor.

It will thus be manifest that a light, simple, durable, cheap and efficient portable structure is provided and one in which different cooking operations can be performed simultaneously and in different parts of the apparatus.

- When it is desired to use the stove holes and not the oven, the damper 50 is closed and if desired the damper 28 may be opened.
- 10 Should it be desired to use the oven at the same time that the stove holes are used, all that is necessary, is to see that the damper 27 is closed and the damper 50 is opened. In this event the heated gases or products 15 of combustion after being circulated across the stove holes will pass through the flue 47 to the oven, and the temperature of the oven can be regulated by the damper 58.
- When it is desired to broil or toast, the 20 damper 50 is closed as are also the stove holes, the burner is then reversed to direct the products of combustion to the tray or broiler, and the damper 28 may be opened to permit the products of combustion to 25 pass therethrough.

What is claimed as new is:—

1. A cooking apparatus embodying a hollow base having stove openings in its top, partitions within the base arranged to 20 form a burner chamber below the stove openings, said partitions spaced from the upright walls of the base and coöperating with said walls to form insulation spaces, a reversible burner arranged in the said 25 chamber and spaced above the bottom thereof, said partitions terminating short of the top of the base of the apparatus, a tapering deflector supported by and depending from the top of the base above the burner for distributing the heated air to the stove openings, additional deflectors arranged within 30 the base to extend across the top of the base and diverging from one side to the opposite side of the base, said deflectors being 35 secured to the said top to prevent warping thereof and engaging the partitions in the 40 45

base to confine the heated air within the area of the stove openings, an outlet other than the stove holes leading from the base, means whereby access may be had to the 50 interior of the base, and a tray adapted to be inserted into the burner chamber beneath the burner and withdrawn therefrom.

2. A cooking apparatus embodying a hollow base having stove openings in its top, 55 partitions within the base arranged to form a burner chamber below the stove openings, said partitions spaced from the upright walls of the base and coöperating with said walls to form insulation spaces, a reversible 60 burner arranged in the said chamber and spaced above the bottom thereof, said partitions terminating short of the top of the base of the apparatus, a tapering deflector supported by and depending from the top 65 of the base above the burner for distributing the heated air to the stove openings, additional deflectors arranged within the base to extend across the top of the base and diverging from one side to the 70 opposite side of the base, said deflectors being secured to the said top to prevent warping thereof and engaging the partitions in the base to confine the heated 75 air within the area of the stove openings, an outlet other than the stove holes leading from the base, means whereby access may be had to the interior of the base, a tray adapted to be inserted into the burner chamber beneath the burner and withdrawn 80 therefrom, and guides formed on the partitions intermediate the burner and bottom of the chamber and beneath which guides the tray is adapted to slide.

In testimony whereof I have signed my 85 name to this specification, in the presence of two subscribing witnesses, on this 24 day of March, A. D. 1914.
